United States Patent Office

Des. 189,605
Patented Jan. 10, 1961

189,605

WARMING STAND

Norman K. Andersen, Pacific Palisades, Calif., assignor
to Reynolds Metals Company, Richmond, Va., a cor-
poration of Delaware

Filed Mar. 11, 1960, Ser. No. 59,701

Term of patent 14 years

(Cl. D81—10)

FIG. 1

FIG. 2

Figure 1 is a top plan view of a warming stand, showing my new design; and

Figure 2 is a side elevational view thereof.

The dish and candle shown in broken lines in Figure 2 are included for illustrative purposes only.

I claim:

The ornamental design for a warming stand, substan-
tially as shown and described.
